The image is a screenshot of a mobile application interface for service management. The top navigation bar includes 'Logout', 'Dashboard', 'Service Requests', 'Service Status', 'Analytics', and 'Help'. Below the navigation, there are three main sections:

- CHARTS & DATA**: A section with a title 'CHARTS & DATA' and a 'Refresh' button. It contains two charts: 'OPEN SERVICE PROBLEMS' (red status) and 'SERVICE AGREEMENT' (green status).
- OPEN SERVICE PROBLEMS**: A table with columns 'Plan Name', 'Problem', 'Provider', and 'Status'. It lists 10 problems, each with a 'View' button.
- SERVICE AGREEMENT**: A table with columns 'Plan', 'Provider', 'SLA', and 'Status'. It lists 10 agreements, each with a 'View' button.

At the bottom, there are sections for 'YOUR TO DO'S' (with a plus icon and a circular progress bar) and 'ANALYTICS' (with a bar chart icon). A 'DASHBOARDS' button is located on the right side of the screen.
